S. A. STRIKER

APPARATUS FOR FORMING CEMENT BLOCKS AND THE LIKE

Filed Dec. 26, 1923

Inventor:

Sidney A. Striker
By Chester W. Brown,

his Attorney.

UNITED STATES PATENT OFFICE.

SIDNEY A. STRIKER, OF DOWNTON GROVE, ILLINOIS.

APPARATUS FOR FORMING CEMENT BLOCKS AND THE LIKE.

Application filed December 26, 1923. Serial No. 682,635.

To all whom it may concern:

Be it known that I, SIDNEY A. STRIKER, a citizen of the United States, residing at the city of Downers Grove, in the county of Du Page and State of Illinois, have invented certain new and useful Improvements in Apparatus for Forming Cement Blocks and the like, of which the following is a specification.

10 My invention relates to apparatus for forming building and other blocks from cement or the like plastic material.

One object of my said invention is to provide a mold in which a plurality of such 15 blocks may be easily and quickly formed from "slush" composition of cement, similar to that used in filling the forms now employed in building construction.

Another object is to provide a simple and 20 inexpensive mold in which the parts are interchangeable, and which can be easily and quickly assembled.

Another object is to provide such an apparatus in which the blocks shall be formed 25 of two separated blocks, joined together by suitable metal ties or rods, such blocks, when laid in a wall will form a continuous "dead air" space between the inner and outer walls.

Another object is to provide such an apparatus in which loose sand is employed to 30 form the core between the two sections of the block.

With the foregoing and other objects in view, which will more particularly appear 35 in the following description, I have shown in the accompanying drawings, and described herein one form of my said apparatus which will illustrate my said invention, and in the accompanying drawings, in 40 which like figures of reference refer to similar parts,

Figure 1 is a top-plan view of the lower 45 section of my apparatus with a portion of the cross partitions removed.

Figure 2 is an elevation of one of the side pieces shown at 4 in Figure 1.

Figure 3 is an elevation of one of the cross partitions shown at 6 in Figure 1.

Figure 4 is a top plan view of the middle 50 section of my apparatus indicated as 2.

Figure 5 is a side elevation of the middle section 2.

Figure 6 is an end view of my apparatus 55 showing a mold with portions broken away to show a cement block molded therein with

the sand core shown between the two separated parts.

Figure 7 is an elevation showing one of the completed cement blocks after being removed from the apparatus, and having the sand core removed therefrom.

In the accompanying drawings I have illustrated the preferred style of my said apparatus and in it I have shown the lower section 1, with the middle section 2 for holding the sand core, and the top section 3, which in construction is identical with the lower section 1. In order to make my apparatus inexpensively, I have constructed it usually from plain boards of the required thickness. In order to provide facilities for easily and quickly assembling the said device, I have provided the side pieces 4 with slots 5 as shown, which are located at the required intervals to form blocks of the sizes 75 required, and are usually one-half the width of the said side pieces in depth. The cross partitions 6, as shown, are usually of the same width as the sides 4, and have slots 80 approximate the ends of a depth of one half the width of said cross partitions 6, at 7, and 7 as shown.

The middle section 2 is preferably formed in the rectangular shape shown, with open 85 top and bottom, the corners being securely fastened together by any usual means. At suitable distances from the middle I have provided cross bonds as 10, 10, which cross said section 2, and extend through openings 90 11 provided in the sides of said section. Openings 12 are provided near the ends of 95 the parts 10, through which may be passed the wedge shaped pins 13, for the purpose of preventing the longitudinal sides of the section 2 from spreading from the effect of pressure within said section in the course of its use in said apparatus.

The upper section 3 is of identical construction as section 1, with sides having slots 100 as in side 4, and with cross partitions 6 having slots as 7 shown in Figure 3.

To assemble my said apparatus for molding cement blocks, the two sides 4 of the lower section are placed on edge as shown in Figure 1, and a suitable number of cross partitions 6 are placed in position, as shown, with the slots 7, 7 of the cross partitions in engagement with the slots 5, 5 of the side 4. When all of the cross partitions have been inserted, the section forms a mold in which 110

a plurality of cement blocks may be molded by merely pouring "slush" cement into said mold and leveling it off even with the top of the side and cross portions. A suitable number of tie wires or rods 15 are now inserted into the said cement, with their upper ends extending upward a sufficient distance to extend through the middle section 2, and into the upper section 3 for the purpose of 10 tying the two sections of each cement block together.

The next section 2 is now superimposed upon the lower section 1, and this section is filled level full of slightly dampened sand as used in foundries, shown at 14 Figure 6. The upper section is now assembled in the same manner as was the lowest section, and this is placed upon the middle section 2, and then poured full of cement, in a manner 20 similar to the section 1. The mold is now filled, and the number of cement blocks have been cast shown. Other similar molds may be filled in turn, and when the cement has hardened sufficiently to permit removing the mold, it is removed by lifting out the cross partitions 6 from the upper section, and removing the sides thereof. The middle section is lifted off the sand, within it, which mostly runs out upon the floor convenient 25 for repeated use, what is left in the mold is swept out, and the lower section 1 is disassembled by removing the cross partitions 6, and then the side pieces 4, and the cement blocks stand as shown in Figure 7, complete, the upper and lower portions being 30 entirely separated by a "dead air" space as shown, and only connected by the numerous wire or tie rods 15 shown.

By the construction shown, it will be apparent that the apparatus is inexpensive in construction, and is easily and quickly assembled, and dis-assembled. By using sand for the core in the middle section, it is easily and quickly shovelled into said form from the floor or other suitable receptacle, and when removed from the form, is in place ready to be used in the next forms to be assembled. By constructing the sides and ends of the lower and upper sections with the slots 5 and 7 therein, they are quickly placed together, and when so placed are locked against separation by any pressure applied within the same in use. In filling the forms, it will be seen that a suitable re-

ceptacle may be employed, and as many 55 forms poured at one time, as the receptacle holds of cement. As the "slush" cement runs to every portion of the form, it will fill it full, without the necessity of tamping, as is customary in most cement blocks now 60 constructed. By employing the "slush" cement, when it hardens, it is much harder than the moist mixture usually employed, and is incapable of dis-integration from moisture, or weather conditions as with 65 many now manufactured from the merely moist mixture. By molding the two sections separately, with the sand core between them, a complete dead air space is formed, and no moisture or cold can seep through 70 the wall from the outside to the inside, as has occurred frequently with the hollow center blocks now in use.

Having thus described my said invention, what I claim and desire to secure by Letters Patent, is the following:—

1. In a device of the class described, the combination of one section composed of sides having slots therein, partitions having slots therein, a second section forming a 80 hollow rectangular space, and a third section composed of sides having slots therein, and partitions having slots therein, substantially as shown and described.

2. In a device of the class described, the combination of a lower section formed of two side pieces having slots half way of their width, partitions having slots engaging said first named slots, a rectangular frame disposed above said lower section, and a third section similar to the first section, disposed above said second section, substantially as shown and described.

3. In a device of the class described, the combination of a knock-down lower section having a plurality of spaces therein for receiving "slush" cement, a rectangular frame of same size disposed upon said first section for holding loose sand to form a core, and a third section disposed above said second section for receiving "slush" cement, with ties or binding rods connecting the lower and upper sections of cement to hold them together when removed from the mold, substantially as shown and described.

In testimony whereof, I have hereunto affixed my signature.

SIDNEY A. STRIKER
